UNITED STATES PATENT OFFICE.

CHARLES SAVRDA, OF NEW YORK, N. Y., ASSIGNOR TO ABBOTT COIN COUNTER COMPANY, OF NEW YORK, N. Y., A CORPORATION OF DELAWARE.

COIN-SEPARATOR.

1,188,494.

Specification of Letters Patent. Patented June 27, 1916.

Application filed February 19, 1916. Serial No. 79,234.

To all whom it may concern:

Be it known that I, CHARLES SAVRDA, a citizen of Austria, and residing at New York, in the county of New York and State 5 of New York, have invented certain new and useful Improvements in Coin-Separators, of which the following is a specification, such as will enable those skilled in the art to which it appertains to make and use the

20 same.

This invention relates to devices for separating coins, and the object thereof is to provide an improved device of this class which I call a gravity separator, and by 15 means of which coins of any denomination and in any amounts may be quickly and easily separated and deposited in separate receptacles from which they may be removed and stored or packed in the usual or 20 any preferred way.

The invention is fully disclosed in the following specification, of which the accompanying drawing forms a part, in which the separate parts of my improvement are 25 designated by suitable reference characters in each of the views, and in which:—

Figure 1 is a plan view of my improved gravity coin separator; Fig. 2 a front view thereof; and, Fig. 3 a central vertical 30 section on the line 3—3 of Fig. 2.

In the accompanying drawing, I have shown my improved coin separator designed for use in separating half dollars, quarters, nickels, pennies and dimes and, in the practice 35 of my invention for this purpose, I provide a box or casing *a* composed, as shown, of vertical side walls *a*² and open at the front and back and having a top plate *a*³ above which is a general coin receptacle *a*⁴ formed by front and back plates *a*⁵ and *a*⁶ and raised portions of the side walls *a*².

At the front of the device, the top plate *a*³ is provided with circular apertures *b* 45 designed to pass all the coins named, except half dollars, and these apertures are preferably formed in a supplemental sheet metal plate secured in position with the front edge of the top plate *a*³.

Within the box or casing *a* are placed diagonally arranged and oppositely inclined separator plates *c*, *d* and *e*, counting from the top downwardly, and in the bottom of the box or casing is a drawer *f* adapted to be 50 withdrawn and inserted from the front of

the box or casing and provided with a handle *f*².

Beneath the first separator plate *c* is a slide plate *g* parallel with said separator plate, and beneath the separator plate *d* is a slide 60 plate *h* parallel with said separator and at the foot or bottom edge of the separator plates *c*, *d* and *e* are coin receptacles *i*, *j* and *k* consisting of oblong box-shaped devices provided respectively with end pins *i*², *j*² 65 and *k*² adapted to enter corresponding bayonet slots *i*³, *j*³ and *k*³ in the front and back edges of the side walls *a*² of the box or casing, and in this way the coin receptacles *i*, *j* and *k* may be inserted into position in the box or casing and removed therefrom whenever desired.

The front and back dimensions of the slide plates *g* and *h* are less than the corresponding dimensions of the separator plates 75 *c* and *d* whereby open spaces *m* and *m*² are formed between the bottom edges of the separate plates *c* and *d* and the coin receptacles *i* and *j*.

The separator plates *c*, *d* and *e* are provided respectively with circular apertures *c*², *d*² and *e*² of different dimensions, and in the use of this device all the coins to be separated, including half dollars, quarters, nickels, pennies and dimes are placed in 80 the receptacle *a*⁴ at the top of the box or casing, and all of said coins except the half dollars may be passed through the apertures *b*, and will fall onto the separator plate *c*. In the passage of said coins downwardly 90 over the separator plate *c* all, except quarters will pass through the circular apertures *c*², and the quarters will pass downwardly over the separator plate into the receptacle *i*, while all the other coins in passing 95 through the apertures *c*² will fall onto the slide plate *g* and move downwardly thereover onto the separator plate *d*, and the nickels will slide downwardly over said separator plate *d* into the receptacle *j*, while 100 the pennies and dimes will pass through the apertures *d*² and will fall onto the slide plate *h* from which they will slide onto the separator plate *e* and will pass downwardly 105 thereover, and in this operation the dimes will pass through the apertures *e*² and fall into the drawer *f*, while the pennies will slide downwardly over the separator plate *e* and fall into the receptacle *k*.

After the coins have been placed in the 110

receptacle a^4 , as hereinbefore described, they are manipulated by hand so as to pass them all over the apertures b , or that part of the top plate having said apertures in it, and 5 this operation may be quickly and easily performed, and during this operation all the coins except the half dollar pieces will pass through the apertures b and be separated and deposited in the receptacles i, j, k and f 10 as hereinbefore described, while the half dollars alone will remain in the receptacle a^4 and may be removed therefrom.

My invention is not limited in its use to 15 coins of any particular denomination and may be used in connection with coins of all denominations, or for the purpose of separating the same, all that is necessary being to properly arrange the separator plates and 20 slide plates and to use the required number of said plates, and to have the apertures in said separator plates of the desired size according to the coins that are to pass there- 25 through in the operation of the device.

My invention is also not limited to any 30 particular form for the receptacles i, j , and f but, in their preferred form and use said receptacles are made detachable, and my invention is also not limited to any particular form or construction of the box or casing a , 35 and said box or casing may be made in any desired manner, and may be entirely enclosed if desired.

The construction shown and described involves four separators, namely, the top plate 35 a^3 and the inclined separator plates c, d and e , it being understood that the largest coins placed on the top plate or in the top receptacle are left there and do not pass through the apertures b . All the other sizes or 40 denominations of coins pass through the apertures b onto the separator plate c , and the largest size or denomination pass into the receptacle i , while all the rest pass through the separator plates c and fall onto the slide 45 plate g from which they pass onto the separator plate d , and the next largest size or denomination fall into the receptacles j , while the others pass through the separator plate d onto the slide plate h from which they pass 50 onto the separator plate e , while the coins of larger size or denomination that fall onto the separator plate e pass into the receptacle k , and the smallest coins pass into the 55 drawer or receptacle f , and applicant is thus able to separate five different denominations or sizes of coins with the use of only three inclined separator plates.

Having fully described my invention, what I claim as new and desire to secure by 60 Letters Patent, is:—

1. A gravity coin separator comprising

an upright box or casing provided at the top thereof with a coin receptacle the bottom of which is provided at one side thereof with apertures of predetermined dimensions, downwardly inclined and alternately arranged separator plates within said box or casing and placed one above another and provided with apertures of predetermined dimensions, receptacles placed under the 65 bottom edges of said separator plates at the opposite sides of the box or casing and adapted to receive coins which pass downwardly thereover, inclined slide plates placed beneath all the separator plates except the bottom one, and a removable receptacle placed under the bottom separator plate.

2. A gravity coin separator comprising an upright box or casing provided at the top 70 thereof with a coin receptacle having a flat bottom provided adjacent to one side edge thereof with apertures of predetermined dimensions, downwardly inclined and alternately arranged separator plates within said 75 box or casing and placed one above another and provided with apertures of predetermined dimensions, detachable receptacles placed on the bottom edges of said separator plates at the opposite sides of the box or 80 casing and adapted to receive coins which pass downwardly over said separator plates, inclined slide plates placed beneath all the separator plates except the bottom one, and a removable receptacle placed under the 85 bottom separator plate.

3. A gravity coin separator comprising an upright box or casing provided at the top 90 thereof with a coin receptacle having a flat bottom provided with apertures of predetermined dimensions and adapted to serve as a separator plate, downwardly inclined and oppositely and alternately arranged separator plates within said box or casing and placed one above another and provided with 95 apertures of predetermined dimensions, detachable receptacles placed under the bottom edges of said inclined separator plates and at the opposite sides of the box or casing, slide plates placed beneath all the inclined 100 separator plates except the bottom one, and a removable receptacle placed under the bottom separator plate.

In testimony that I claim the foregoing as my invention I have signed my name in 105 presence of the subscribing witnesses this 110 17th day of February, 1916.

CHARLES SAVRDA.
